STARTING AND OPERATING CIRCUIT FOR FLUORESCENT LAMPS

William S. H. Hamilton, Larchmont, N. Y.

Application July 28, 1952, Serial No. 301,252

6 Claims. (Cl. 315—100)

This invention relates to certain new and useful improvements in starting and operating circuits for A. C. and D. C. fluorescent lamps, particularly long hot cathode A. C. fluorescent lamps, such as the 48", T-12 type, in which the filamentary electrodes have to be heated to cause the lamp to fire. Most of the commercial circuits for lamps of this type employ the glow switch type of starter which gives satisfactory results where the minimum cost is desired and where there are a considerable number of lamps connected in a group. The glow switch type of starter, however, is often uncertain and erratic in operation, as, while some starters of this type, when the line circuit is turned on, will at certain periods or under certain conditions of use, cause the filaments to glow almost immediately and the lamp to fire shortly thereafter, the same type of starters at other times will merely when first operated cause a momentary flicker in the filaments of the lamp followed by a long delay, during which time lamp is dark, before the starter operates again to close the circuit through the filaments so that the normal starting operation will commence. This erratic starter action is particularly objectionable in the use of single lamps in individual rooms or in locations where the lamps are subject to vibration.

Other types of thermostatic starters are also objectionable in use in attempting to start a hard starting lamp where the starter has to repeat one or more times, or where a lamp has been in use and cut out of operation and it is desired to restart it, on account of the time delay involved due to the necessity of the starter having to go through its complete cycle of operation in repeating and restarting actions.

The object of the present invention is to provide means to overcome the above stated objections to glow switch and other thermostatic type starters and circuits employing them, and to provide circuit arrangements employing a thermostatic type starter switch in conjunction with a controlling relay cooperating in such manner as to produce a starting structure which is more accurate, rugged and reliable in operation than a glow switch or other conventional type of thermostatic starter in effecting the quick starting and restarting of lamps of the type described or similar lamps, and which has the further advantage of always giving a signal glow in the filaments of the lamp itself immediately when the line circuit is closed indicating that the lamp is in good order for use.

The present application is a continuation-in-part of my prior application Serial No. 171,495, filed June 30, 1950, so far as it applies to the starter structure disclosed originally shown in Fig. 6 of said prior application Serial No. 171,495 and its transfer to and incorporation as Fig. 1 in this application.

In the accompanying drawings I have shown certain new circuits for carrying the present invention into practical effect, in which drawings:

Fig. 1 is a diagrammatic view of a form of circuit for operation of lamps on A. C. and which embodies my improved starter arrangement.

Fig. 2 is a diagrammatic view of a circuit similar to Fig. 1 showing a modification in the construction.

Fig. 3 is a diagrammatic view showing the embodiment of the invention in a circuit adapted for operation on either A. C. or D. C.

Fig. 4 shows a modification of the circuit shown in Fig. 3.

Referring now more particularly to Fig. 1 of the draw-

2

ing, 1 represents the gas containing envelope of the lamp having the filamentary electrodes 2 and 3, and 4 and 5 are lamp operating and line, or supply, circuit conductors for supplying current from a suitable

5 A. C. source to the lamp and starter elements located in a can or casing 10. These conductors are connected at the terminals B, W to the terminal leads of the primary 6 of an inductive reactance device such as the reactor-transformer 7, which is thus connected across the line. From the secondary 8 of this reactor-transformer leads a feed conductor 9 which is connected to the input end of the filament 2, and from the output end of the filament 2 extends a preheating or return conductor 11 having divided portions or branches 11', 15, 12, the latter being connected directly to the input end of filament 3, to the output end of which is connected a conductor 25.

The branches 11, 12 are normally coupled by the automatically closing switch member 13 of a relay switch 20 including a second automatically closing switch member 14 and a relay coil 15, and in the branch 12 is arranged a thermostatic switch heater 16. The output end of filament 3 is connected with the conductor 5 by the operating conductor or return conductor portion 12' 25 across which is connected a by-pass or shunt circuit conductor 15' comprising branches 15^a, 15^b, 15^c normally connected by the relay switch 14 and the thermostatic starter having normally closed contacts 17—18. In the connection 12' is arranged the normally deenergized 30 relay coil 15 which controls both switches 13 and 14. A condenser 13' is placed across the contacts of switch 13 to prevent arcing when the contacts open.

In the operation of the circuit shown in Fig. 1, when the A. C. line circuit is closed, the reactor-transformer 35 7 is energized through terminals 4—5, which in turn causes additional voltage to be impressed on conductor 9. Current then flows from line terminal 4 through the reactor-transformer 7 and conductor 9 to and through filament 2 of the lamp, through conductor 11 and switch contacts 13, conductor 12 and heater 16 to and through the filament 3 and conductor 15' to and through the closed thermostatic contacts 17—18 of the starter 10 conductors 15^b and 15^c and switch contacts 14 to line terminal 5. This provides for the flow of normal preheating current for the filaments of the lamp as determined by the design of the reactor-transformer.

Under this condition the contacts 17—18 of the starter short circuit the relay coil 15 and prevent it from being energized. When a sufficient time has elapsed to heat the filaments of the lamp to the proper temperature, the thermostatic contacts 17—18 of the starter open and allow the coil 15 of the relay to be energized. The energized relay coil then opens switch 13 to break the preheating circuit. The opening of switch 13 gives 50 an inductive kick to start the lamp. Switch 14 is also opened at the same time. On the lamp firing, current flows through the lamp and via conductor 12' and through the relay coil 15 which holds the switches 13—14 open.

The switch 14 is arranged in series with the normally closed thermostatic contacts 17—18 of the starter 10, so that when the contacts 17—18 reclose, due to current being removed from the heater 16 by the opening of switch 13, contacts 17—18 cannot reclose the short circuit around relay coil 15, as switch 14 will be open. The lamp then continues to operate with relay coil 15 holding both switches 13—14 open as long as the line circuit is closed. If the line circuit is interrupted, however, coil 15 is deenergized and switches 13—14 60 reclose immediately. When the line circuit is again closed, the starting action above described is again initiated.

This circuit arrangement is positive and reliable as long as the lamp is in good order and ensures a glow of the filaments immediately upon closing the line circuit, which indicates that the line circuit is closed and that the lamp will soon fire. It should be understood that while the description has been confined to a particular type of lamp, the principle applies to any of the A. C. fluorescent lamps having filamentary electrodes 75 except those of the "instant start" type (which are short-circuited within the lamp), and that the voltages ap-

3

plied would depend on the voltage of the A. C. line, the requirements of the lamp, and the design of the reactor-transformer, or reactor.

If the lamp (Figure 1) does not fire on the first attempt, the starter will make repeated attempts to start it, and if it does not succeed will show by the continued applications and cutting off of the preheating current that the lamp is defective and should be replaced. This 10 starter requires the use of four leads.

As stated, the circuit of Fig. 1 provides a starter which overcomes the specified objections to the glow switch type of starter and which is more rugged and more certain and reliable in action and gives a signal glow in the lamp filaments immediately upon the line circuit being closed indicating that the lamp is in good order and should start within its normal time period. The 15 use of the circuit arrangement and relay of Fig. 1 also insures more accurate control of the circuit, less delay in starting a good lamp even when a repeat action is necessary, and quicker restarting actions when desired than is possible by the use of a glow switch or a conventional type thermostatic starter.

Fig. 2 shows a circuit similar to that of Fig. 1 except for the use of a simple reactor 7^a in place of the reactor-transformer 7 , and the operation of Fig. 2 circuit is the same as that above described with relation to Fig. 1 circuit. Generally speaking, the two circuits are functionally equivalent though having different operating characteristics giving each a working advantage over the other under different working conditions.

Fig. 3 shows a circuit designed for the specific purpose of effecting starting of a lamp under low temperature conditions, i. e., 0° F. and lower. It has the advantage that the starting current and the operating current can be separately adjusted. This enables a higher starting current to be used than can be obtained from the ballast reactor ordinarily used for a particular lamp, while at the same time permitting the operating current to be adjusted to the proper current value after the lamp has fired. This circuit also allows a quick restarting action to be obtained after the lamp has been operating a few seconds and the line current has been cut off and is again let on.

As shown, this circuit comprises a feed conductor 9^a containing a reactor 21^1 , and leading to one terminal of the filament 2^a , from the other terminal of which leads a return conductor 11^a comprising a section 11^{a1} connected to one terminal of the filament 3^a , a section 11^{a2} connected to the line terminal 5 , a section 11^{a3} connected to the other terminal of filament 3^a , and a section 11^{a4} arranged between the sections 11^{a2} and the section 11^a . Section 11^a has a gap normally closed by a relay switch 13^1 and contains a current limiting resistor 8^m and a heater 16^1 . Extending across the conductor sections 11^{a2} and 11^{a3} is a conductor 15^a containing the relay coil 15^m , ballast lamp 26^1 and current limiting resistance 8^a , forming part of the operating circuit which is shunted or short circuited when the switch 14^1 and starter contacts 24^1 are closed but which is connected in series with the lamp when the lamp is operating. Switches 13^1 , 14^1 and starter contacts 24^1 , when closed, establish a starting or preheating circuit ready for operation when the line circuit is closed. The starter in this circuit has four terminals only, viz., x , y , x' , y' .

In this circuit in starting, current flows from one side of the line, or supply, circuit, which may be a source of either alternating current or direct current, through the reactor 21^1 , through filament 2^a of the fluorescent lamp, through the normally closed contacts of the relay lamp, through the normally closed contacts of the relay switch 13^1 through resistor 8^m , to terminal x of the switch 13^1 through resistor 8^m , to terminal x of the starter. Thence the current flows through heater 16^1 to terminal x' of the starter, through the other filament 3^a of the fluorescent lamp, to terminal y' of the starter, through starter contacts 24^1 to terminal y of the starter, through the normally closed contacts of the relay switch 14^1 and thence to the other side of the line or supply, circuit. During this preheating action, resistor 8^m , the ballast lamp 26^1 and relay coil 15^m are short circuited by switch 14^1 and starter contacts 24^1 , so that the relay coil 15^m is kept de-energized. The amount of preheating current can be adjusted by resistor 8^m .

Preheating current continues to flow until heater 16^1 of the starter heats up the starter contacts 24^1 sufficiently to cause them to open. When they open, they remove

the short circuit around resistance 8^m , the ballast lamp 26^1 and coil 15^m of the relay, thus energizing the coil and causing the relay to open switches 13^1 and 14^1 .

Switch 13^1 , on opening, breaks the preheating circuit and causes the reactor to give an inductive kick to start the lamp. The lamp if in normal condition fires, and current flowing through the lamp flows through resistor 8^a , the ballast lamp 26^1 and relay coil 15^m , thus keeping the relay coil energized and switches 13^1 and 14^1 open. Switch 14^1 being open prevents the starter contacts 24^1 from reclosing the short circuit around resistance 8^m , the ballast lamp 26^1 and relay coil 15^m , when they reclose upon the cooling of heater 16^1 . The operating current can be adjusted to any desired value by the selection of the proper size ballast lamp and the proper resistance of resistor 8^m .

The operating circuit is from one side of the line, through the reactor, to one filament of the fluorescent lamp, through the gas in the lamp itself to the other filament, thence through resistance 8^a , the ballast lamp 26^1 and relay coil 15^m to the other side of the line.

If the line circuit is opened while the lamp is operating, the relay coil 15^m will be de-energized and allow switches 13^1 and 14^1 to reclose immediately, ready for another starting action. As long as the lamp has operated along enough for the contacts 24^1 of the starter to reclose (which is only a few seconds), this circuit is always ready for a starting or restarting action, and there will be a glow in both filaments as soon as the line circuit is closed.

Fig. 4 shows a circuit which is similar in all respects to Fig. 3 with the following exceptions: the inductive reactance device 21^1 , instead of being connected in the feed conductor 9^a to filament 2^a , is connected in the opposite side of the line, namely, in feed conductor 11^a from the line terminal 5 . Also in Fig. 4 the diagrammatic illustration of the four contact pins x , y and x' , y' has been omitted. Finally, the current controlling resistance 8^{a1} is omitted, the operating current being controlled entirely by the ballast lamp.

If the lamp (Figure 3) does not fire on the first attempt, the starter will make repeated attempts to restart it, and if it does not succeed will show by its continued applications and removal of current that the lamp is defective and should be replaced. The starter in this circuit requires the use of four leads.

Practical use of the starter organizations herein disclosed has shown that the starter relay circuits work with greater efficiency than ordinary starters, and will fire lamps which glow switch starters and other thermostatic starters will not fire, due to the rapid breaking of the preheating circuit by the relay contacts which is much more rapid than is obtained by any of the starters now generally employed. This prevents the troubles and annoyances often caused in starting lamps, particularly those of the type described, in using the glow switch type of starter and other starters.

It will be understood, of course, that while I have shown certain ways of carrying my invention into practical effect, other ways or means equivalent thereto, and falling within the scope of the appended claims, may be employed without departing from the spirit of my invention. It will also be understood that while I have set forth the disadvantages of circuits using straight thermal and glow switch types of starters as hereinbefore constructed and used, and the advantages attained by the use of a thermostatic type of starter, I do not limit myself to the use, except when specified in the claims, to any particular type of starter or time delay device which may be used to carry my invention into practical effect.

What is claimed is:

1. In combination, a gaseous electric discharge device having two electrodes constructed to receive preheating current, a supply circuit, a relay having an operating coil and two sets of normally closed contacts, means including an inductive reactance device and the operating coil of said relay for connecting said electrodes to said supply circuit, a delay device having an operating circuit and normally closed contacts, and an electrode preheating circuit capable of producing firing temperature electrode heating, said circuit extending from one side of a voltage source to the opposite side of said source and including in series connection said inductive reactance device, said two electrodes, one set of relay contacts, said delay device operating circuit and a cir-

cuit connected in shunt with said relay switch operating coil, said shunt circuit including in series connection the contacts of said delay device and the second set of relay contacts so that the opening of said delay contacts causes the energization of said operating coil and the consequent opening of said sets of relay contacts, the opening of said first set causing the discharge device to fire by an inductive voltage kick, said first set of contacts being connected in shunt with said electrodes, and the opening of the second set of relay contacts maintaining said operating coil energized after the delay device contacts have reclosed.

2. The combination set forth in claim 1 in which the delay device is a thermostatic switch having a heating circuit and normally closed contacts, the said heating circuit being included in series connection with the electrode preheating circuit.

3. The combination set forth in claim 1 in which one of the electrodes is connected to one side of the supply circuit through a circuit including an inductive reactance device, and the other electrode is connected to the opposite side of the supply circuit through a circuit including the operating coil of the relay.

4. In combination a gaseous electric discharge device having first and second electrodes constructed to receive preheating current, a supply circuit, a relay having two sets of normally closed contacts, means including an inductive reactance device and the operating coil of said relay for connecting said electrodes to said supply circuit, a delay device having an operating circuit and normally closed contacts, and an electrode preheating circuit capable of producing firing temperature electrode heating, said circuit extending from one side of a voltage source to the opposite side of said source and including in series connection said inductive reactance device, and in sequence the first electrode, one set of relay contacts, said delay device operating circuit, the second electrode and a circuit connected in shunt with said relay switch operating coil, said shunt circuit including in series connection the contacts of said delay device and the second set of relay contacts so that the opening of said delay contacts causes the energization of said operating coil and the consequent opening of said sets of relay contacts, the opening of said first set causing the discharge device to fire by an inductive voltage kick, said first set of said contacts being connected in shunt with said electrodes, and the opening of the second set of relay contacts maintaining said operating coil energized after the delay device contacts have reclosed.

5. The combination set forth in claim 4 in which one of the electrodes is connected to one side of the supply circuit through a circuit including an inductive reactance device, and the other electrode is connected to the opposite side of the supply circuit through a circuit including the operating coil of the relay.

6. In combination a gaseous electric discharge device having first and second electrodes constructed to receive preheating current, a supply circuit, a relay having an operating coil and two sets of normally closed contacts, means including an inductive reactance device and the operating coil of said relay for connecting said electrodes to said supply circuit, a current controlling device connected in series with said coil, a delay device having an operating circuit and normally closed contacts, and an electrode preheating circuit capable of producing firing temperature electrode heating, said circuit extending from one side of a voltage source to the opposite side of said source and including in series connection said inductive reactance device, the first electrode, a preheating current limiting device, one set of relay contacts, the second electrode, said delay device operating circuit and a circuit connected in shunt with said series-connected relay operating coil and current controlling device, said shunt circuit including in series connection the contacts of said delay device and the second set of relay contacts so that the opening of said delay contacts causes the energization of said relay operating coil and the consequent opening of said sets of relay contacts, the opening of said first set causing the discharge device to fire by an inductive voltage kick, said first set of contacts being connected in shunt with said electrodes, and the opening of the second set of relay contacts maintaining said operating coil energized after the delay device contacts have reclosed.
